UNITED STATES PATENT OFFICE.

ROSS JOHN ELLSWORTH, OF ELIZABETH, NEW JERSEY, ASSIGNOR TO SIMMONS COMPANY, OF KENOSHA, WISCONSIN, A CORPORATION OF DELAWARE.

CRIB TRIP LOCK.

Application filed September 3, 1920. Serial No. 407,995.

My invention relates to improvements in crib trip-locks, and has particular reference to a type of foot-controlled latch or lock for the sliding side of an ordinary crib.

5 The primary object of the invention is to provide a simple, economical, readily accessible, efficient, crib-lock of the class described, and one which may be manipulated simply and quickly whenever occasion requires.

10 In the drawings, which illustrate my invention as applied to a sliding crib side on a crib of approved construction—

Fig. 1 is a fragmentary view in side elevation of a portion of the crib and locking mechanism;

Fig. 2 is a section taken on the line 2—2 of Fig. 1; and Fig. 3 is a view similar to Fig. 2, but showing the parts in unlocked position.

Referring to the drawings, it will be understood that the crib is of tubular construction as to the corner posts 10, the frame of the crib which supports the spring or mattress being composed of angle iron members including side rails 11. Said supporting frame may, if desired, have its ends supported by and secured to cross-tubes 12.

The sliding crib side is constructed with vertical frame tubes 13 and horizontal frame tubes 14, the vertical frame tubes 13 being suitably organized to slide upon the stationary vertical guide-rods 15 at each end of the crib. Preferably, the guide-rods 15 are substantial enough to prevent the bottom of the sliding side from swinging appreciably outside of the vertical plane in which the sliding gate or side normally travels.

The lower ends of the side tubes 13 and the bottom tube 14 of the sliding crib side are joined by means of ferrules 16 and 17 suitably united together. From the ferrule 17 projects an axially horizontal locking pin 18 with which the latch mechanism operates.

The latch proper comprises a substantially V-shaped hook 19, the upper end of which is pivoted upon the forwardly and downwardly projecting arm 20 of a small bracket 21 rigidly secured to the end of the angle iron 11 by any suitable means, such as rivets 22. Said latch or hook 19 is formed with a notch 23 which, in the position shown in Fig. 2, serves to support and lock the cooperating pin 18, and thereby maintain the sliding gate in elevated position.

The unlatching of the crib side is effected by means of a foot-actuated arm or pedal 24, said member comprising a strap-like finger depending from and rigidly secured to the center of a horizontal trip-rod 25. Said trip-rod 25 is rotatably supported as to its central portion, in a small bracket comprising a strap 26 secured to the side of the angle iron 11 and having its ends turned up, as shown at 27, and perforated to accommodate the trip-rod 25.

65 The outer ends of the trip-rod 25 are bent at right-angles, as shown at 28, the lower ends of said depending parts 28 being reversely bent to form horizontal, inwardly-extending tripping pins 29. Each of the 70 tripping pins 29 is arranged to operate in a cam slot 30 formed in the lower end of the V-shaped latch member 19.

The length of the slot 30 is obviously controlled by the spacing between the latch 75 pivot 31 and the aperture in the arm 20, which accommodates the outer end of the trip-rod 25.

The operation of the device is simplicity itself. When the crib side is raised, the 80 parts occupy the position shown in Fig. 2, with the latch pin 18 securely locked in the notch 23 of the latch, thereby preventing the crib side from falling. Whenever it is desired to lower the crib side in order to gain 85 better access to the interior of the crib, the mother presses the lower end of the trigger 24 inwardly with her foot, thereby moving the latch 19 into the position shown in Fig. 3. This results in the release of the lock- 90 pins 18 at each end of the crib, and the crib side is thereby permitted to descend.

The parts, by reason of the superior gravity of the trigger 24, tend normally to assume the position shown in Fig. 2, and when in 95 such position the latch 19 presents an inclined cam surface 32 lying in the path of the pin 18 when the crib side is elevated. Hence, when the crib side is raised for the purpose of locking it in elevated position, 100 the pin 18 engages the edge 32 of the latch 19 and moves the latter back into such position that the pin 18 will pass over the barb 33 of the hook, which will then swing forward into the position shown in Fig. 2, thus 105 automatically locking the crib side in elevated position without further attention from the operator.

The details of construction and operation herein described are merely illustrative of a single application of my invention, the scope of which should be determined by reference to the appended claims.

I claim—

1. In a crib the combination of a main frame, a vertically adjustable gate at the side of the main frame, a pair of spaced hangers having the upper extremities pivoted on the main frame and having notches adapted to engage the gate for holding the latter in the elevated position and a rod extending between the hangers and independently pivoted on the main frame and provided with cranks at the ends connected to said hangers and operable to engage or disengage said hangers and said gate and foot

controlled means on the rod for oscillating the latter to so operate said hangers. 20

2. In a crib the combination of a main frame having a vertically adjustable gate at the side thereof, a pair of spaced latches pivoted on the main frame and having notches adapted to engage with the gate to hold the latter in the elevated position, a rod extending between the latches and pivoted on the main frame at a distance from the pivotal axis of the latches and having crank portions at the ends engaging slots in the latches for operating the latter, and an operating member on the rod for oscillating the crank portions of the latter to move the latches out of engagement with the gate. 25

ROSS JOHN ELLSWORTH.
